(57) **CLAIM**

The ornamental design for a tiled globe assembly, as shown and described.

DESCRIPTION

FIG. 1 is a side view of a tiled globe assembly showing my new design.

FIG. 2 is a top plan view of one hexagonal segment of the tiled globe assembly, shown separately for completeness of illustration.

FIG. 3 is a bottom plan view thereof.

FIG. 4 is a side elevational view thereof.

FIG. 5 is a bottom perspective view thereof.

FIG. 6 is a top plan view of one pentagonal segment of the tiled globe assembly of FIG. 1, shown separately for completeness of illustration.

FIG. 7 is a bottom plan view thereof.

FIG. 8 is a side elevational view thereof.

FIG. 9 is a bottom perspective view thereof; and, FIG. 10 is a side view of the tiled globe assembly of FIG. 1, shown with a hexagonal segment in an alternate position.

1 Claim, 6 Drawing Sheets
